UNITED STATES PATENT OFFICE

139,625

DESIGN FOR A CLIMBER

Robert L. Woodbury, United States Army,
Litchfield, Conn.

Application March 27, 1944, Serial No. 113,052

Term of patent 14 years

(Cl. D7—6)

To all whom it may concern:

Be it known that I, Robert L. Woodbury, United States Army, a citizen of the United States, residing at Litchfield, Connecticut, have invented a new, original, and ornamental Design for a Climber, of which the following is a specification, reference being had to the accompanying drawing, forming a part thereof.

Fig. 1 is a front elevational view of a climber, showing my new design.

Fig. 2. is a side elevational view thereof.

Fig. 3 is a side elevational view of the opposite side, and

Fig. 4 is a plan view thereof.

I claim:

The ornamental design for a climber, as shown.

ROBERT L. WOODBURY.
